FIRING MECHANISM FOR AN AUTOMATIC FIREARM

William R. Kunz, Springfield, Mass., assignor to the United States of America as represented by the Secretary of the Army

Application August 21, 1957, Serial No. 679,802

5 Claims. (Cl. 89—131)

(Granted under Title 35, U.S. Code (1952), sec. 266)

The invention described herein may be manufactured and used by or for the Government for governmental purposes without the payment of any royalty thereon.

This invention relates to automatic firearms and more particularly to firing mechanisms therefor whereby a firearm may be selectively adjusted to fire a single round, short bursts of a predetermined number of rounds, or continuously.

It is one of the objects of this invention to provide for automatic firearms a firing mechanism through which a firearm may be operated at the optimum rate to obtain the maximum benefits from continuous fire at a high rate, while being conservative in the expenditure of ammunition, with the continuous operation being automatically stopped after a predetermined burst quicker than is possible through manual release of the operating trigger.

It is another object of this invention to provide for firearms which utilize a hammer-activated firing pin to fire a chambered cartridge, a firing mechanism whereby such a firearm may be fired continuously as long as the trigger is held in firing position or which automatically interrupts the operation of the firearm after a single round has been fired or after a short burst of a predetermined number of rounds.

It is a further object of this invention to provide for such firearms a firing mechanism in which a Geneva device cooperates with the hammer in controlling the number of rounds fired while the trigger is held in firing position.

It is still another object of this invention to provide for such a firing mechanism a selector which serves both to move a coupler into selective relationship with the Geneva device and to selectively block the movement of the Geneva device and thereby act as a safety by making the firearm inoperative.

It is another and still further object of this invention to provide for such a firing mechanism a device for safetying the firearm regardless of whether the hammer is in firing or cock position.

It is still another and further object of this invention to provide a firing mechanism for selectively adapting a firearm to a number of operating conditions and which is simple and rugged in construction and positive in operation.

The specific nature of the invention as well as other objects and advantages thereof will clearly appear from a description of a preferred embodiment as shown in the accompanying drawings in which:

Fig. 1 is a partially cross-sectioned side view of the firearm showing the selector in "Safe" position;

Fig. 2 is the same as Fig. 1 but showing the hammer retracted by the bolt, the trigger in the retracted position and the selector indexed for limited burst firing;

Fig. 3 is an enlarged view taken along line 3—3 of Fig. 4;

Fig. 4 is the same as Fig. 1 but showing the trigger in

retracted position and the selector indexed for single-shot firing;

Fig. 5 is a view taken along line 5—5 of Fig. 1;

Fig. 6 is a perspective view of the trigger mechanism; and

Fig. 7 is an enlarged perspective view showing an optional design of the Geneva.

Shown in the figures is a firearm receiver 12 in which a bolt 14 is mounted for sliding reciprocal movement with such bolt being provided with a firing pin 16. A trigger housing 18 depends from the underside of receiver 12 and is provided with a pair of laterally-spaced sides 20 through which a pin 22 is transversely mounted adjacent the front ends. A semicircular hammer 24 is pivotally mounted at one end on pin 22 so that the free end thereof, noted at 26, swings upwardly and forwardly to a firing position wherein the rear end of firing pin 16 is engaged to fire a cartridge chambered in the firearm barrel (not shown). Hammer 24 is actuated from such firing position to a retracted position by bolt 14 through the sliding engagement of free end 26 with the rear end of the bolt when moving to recoil position. Hammer 24 is maintained in retracted position during movement of the bolt 14 to and from recoil position by the sliding engagement of free end 26 with the bottom side of the bolt. A spring 28 biases hammer 24 to the firing position.

A trigger 30 is pivotally mounted in trigger housing 18 on a pin 32 which extends transversely through the trigger housing to the rear of and below pin 22. Trigger 30 includes a finger portion 34 which extends below trigger housing 18 and a sear arm 36 which extends forwardly to engage a catch portion 38 in hammer 24 for releasably holding the hammer in a cock position between the retracted and firing positions thereof. Trigger 30 also includes a selector arm 40 which extends upwardly from pin 32. A spring 42 is disposed between sear arm 36 and the bottom of trigger housing 18 so as to bias finger portion 34 to normal forward position and such sear arm upwardly into hammer engaging position. Upward movement of sear arm 36 is limited by the rearward engagement of selector arm 40 with a rod 43 extending transversely through trigger housing 18.

A Geneva device 44 is rotatably mounted in trigger housing 18 between hammer 24 and selector arm 40 on a transversely disposed axle 46 so as to be engaged for rotation by hammer 24 during pivotal movement thereof, as hereinafter explained. Geneva device 44 includes a gear wheel 48 which is substantially square in configuration and is provided with four sides 50 which are arcuately recessed to form four teeth 52 at the corner portions. Such Geneva device also includes a sprocket wheel 54 with a single sprocket 55 which abuts gear wheel 48 on the right side thereof so as to be in lateral alignment with one of the teeth 52, as is best shown in Fig. 6, and a spacer 56 disposed between gear wheel 48 and the left one of the sides 20.

The arcuately formed sides 50 of gear wheel 48 have a radius similar to that of the outside perimeter of hammer 24 and such gear wheel and hammer are so related that the outer perimeter of the hammer and one of the sides 50 of the gear wheel are in contiguous sliding relationship during movement of such hammer between the firing and cock positions thereof. As axle 46 is mounted through trigger housing 18 above pin 22, the teeth 52, which are in the two upper positions, are positioned in parallel alignment with a line through the centers of such axle and pin during the sliding engagement of one of the sides 50 with hammer 24. Consequently, the rear one of the upwardly disposed teeth 52 extends above the front one thereof when hammer 24 is in engagement with one of the sides 50.

Extending radially outward from free end 26 is a sub-

stantially triangular lug portion 58 disposed for camming engagement with the forward one of the upwardly disposed teeth 52 during movement of hammer 24 from cock to retracted position. Lug portion 58 is so related to gear wheel 48 that the camming engagement therebetween rotates the gear wheel in a counterclockwise direction until the upper ones of the teeth 52 are in parallel alignment with the longitudinal axis of the firearm and out of the path of movement of bolt 14. It is evident that as the forward one of the upwardly-disposed teeth 52 is rotated upwardly, the forward one of the lowermost teeth is rotated forwardly and is received by a recess 60 extending into hammer 24. Recess 60 forms a cog portion 62 which is engageable with the one of the teeth 52 which is rotated into such recess during movement of hammer 24 from retracted to cocked position so that gear wheel 48 continues to be rotated in a counterclockwise direction to bring such gear wheel and hammer into sliding engagement during the remaining movement of the hammer to firing position. Consequently, during an operational cycle of the firearm, Geneva device 44 is rotated 90° by hammer 24 when pivoted to and from retracted position. Furthermore, when gear wheel 48 is held against rotation, by means as hereinafter explained, the engagement of cog portion 62 with such gear wheel 48 blocks the movement of hammer 24 to cock position.

A shaft 64 is mounted transversely through trigger housing 18 so as to pass in front of selector arm 40 at the junction thereof with sear arm 36. Mounted on shaft 64, as hereinafter described, is a coupler 66 provided with a hub portion 68 which receives shaft 64, and an arm portion 70 which extends upwardly from the hub portion between selector arm 40 and Geneva device 44 so that the free end of such arm portion is engageable with the rear one of the uppermost teeth 52 when engageably pivoted forwardly by selector arm 40. A coil spring 72 is operationally disposed between hub portion 68 and trigger housing 18 for torsionally biasing coupler 66 in a counterclockwise direction and linearly biasing such coupler along shaft 64 into normal contact with the left one of the sides 20. Whereby, arm 70 is normally aligned with spacer 56 and is slideable along shaft 64 into alignment with gear wheel 48 and sprocket wheel 54.

Coupler 66 is movable into selective alignment with gear wheel 48 and sprocket wheel 54 by a selector 76 which is fixedly mounted to a rotatable shaft 74 mounted transversely through trigger housing 18. Selector 76 includes a cylindrical hub portion 78 having an axial hole therethrough for receiving shaft 74 as by press fit. An arcuate cam portion 80 extends radially from hub portion 78 for cooperation, as hereinafter described, with a foot portion 82 extending forwardly from hub portion 68.

Cam portion 80 develops angularly, as hereinafter described, in a counterclockwise direction from a leading edge 86 which extends radially from the left end of hub portion 78. Extending angularly to the right, respective to the gun, and in a counterclockwise direction from leading edge 86, is a primary ramp portion 84 which leads to a planar primary step portion 88 disposed parallel to the longitudinal plane of the firearm. A secondary ramp portion 90 extends similarly from primary step portion 88 to a secondary step portion 92 disposed parallel to primary ramp portion 88. Provided on the left side of foot portion 82 is an angular surface 94 which is cammingly engageable by primary ramp portion 84 and secondary ramp portion 90 to translate counterclockwise rotation of selector 76 to lateral movement of coupler 66 towards the right one of the sides 20. Primary and secondary portions 88 and 92 are so disposed that, when in engagement with foot portion 82, arm portion 70 is in engageable alignment with gear wheel 48 and sprocket wheel 54, respectively.

Selector 76 is also disposed relative to Geneva device 44 so that, when the perimeter of secondary step portion 92 is moved to its uppermost position as shown in Fig. 1, 75

gear wheel 48 is engageably blocked from counterclockwise rotation and so acts as a safety to prevent operation of the firearm. When selector 76 is in such "Safe" position, gear wheel 48 is engageably positioned thereby so that the upper ones of the teeth 52 are disposed parallel to the longitudinal axes of the firearm. Whereby, hammer 24 is free to pivot from firing to retracted position but is blocked during movement from retracted to cock position. Thus, it is evident that the firearm may be made "Safe" even when hammer 24 is in firing position as is not possible in most firearms.

Shaft 74 is arranged to extend beyond the right one of the sides 20, and mounted to such extending portion is a radially disposed lever 96 by which selector 76 may be rotated manually. Provided in the free end of lever 96 is a detent 98 which is spring-biased against the face of the adjacent one of the sides 20 and is releasably received by one of four indexing indentations 100 in such side. Such indentations 100 are arranged to successively receive detent 98 when selector 76 is in alignment with spacer 56, when foot portion 82 is in respective engagement with the primary and secondary step portions 88 and 92, and when the selector is in "Safe" position. The indexing indentations 100 are suitably marked to show 20 the operating condition to which the firearm is selectively regulated.

An automatic sear 102 is mounted on the outside of the left one of the sides 20 for sliding movement between a rearward lock position and a forward unlock position. 30 Automatic sear 102 is provided with a lock portion 104 which extends into trigger housing 18 through a longitudinal slot 106. Automatic sear 102 is spring-biased by means (not shown) to lock position and is actuated to the unlock position by the operating mechanism (not 35 shown) of the firearm when bolt 14 is locked in battery position. Lock portion 104 cooperates with a notch 108 extending into hammer 24 from the inside perimeter thereof for releasably locking the hammer in a lock position between the cock and firing positions until bolt 14 40 is locked in battery position, at which time automatic sear 102 is actuated to release hammer 24, if in engagement therewith, or is moved out of the way for uninterrupted movement of the hammer to firing position when released from engagement with sear arm 36.

Operation

To regulate the firearm for firing only a single round each time trigger 30 is actuated, lever 96 is rotated to the one of the indexing indentations 100 whereby coupler 50 66 is moved by selector 76 into position for arm portion 70 to be engageably aligned with gear wheel 48. Thus, starting with the firearm charged so that hammer 24 is engaged in cock position by sear arm 36, such sear arm is disengaged from catch portion 38 to release the hammer for engagement with firing pin 16 to fire the chambered cartridge when trigger 30 is actuated to firing position. During the initial movement of hammer 24 from cock position, the one of the teeth 52 which is received by recess 60 and engaged by cog portion 62 is rotated 55 upwardly and in a counterclockwise direction by such cog portion until the following one of the sides 50 and the outside perimeter of hammer 24 align for sliding engagement during the remaining travel of the hammer to firing position.

As bolt 14 recoils responsive to the discharge, hammer 24 is actuated thereby to retracted position. When hammer 24 approaches retracted position, lug portion 58 thereon cammingly engages the one of the teeth 52, moved by cog portion 62 upwardly during rotation of the hammer to firing position, to continue the counterclockwise rotation of gear wheel 48 until such tooth is in longitudinal alignment, respective to the firearm, with the other one of the upwardly-disposed teeth. Consequently the next one of the teeth 52 is moved into recess 60 in 60 position to be engaged by cog portion 62 when hammer

24 pivots from retracted position with the counterrecoil of bolt 14. With trigger 30 in firing position, coupler 66 is pivoted forwardly by selector arm 40 into position to be engaged by the rearward one of the uppermost teeth 52. Consequently, gear wheel 48 is blocked from rotation and thereby, because of the engagement of cog portion 62 with the one of the teeth 52 received by recess 60, hammer 24 is prevented from proceeding to cock position. When trigger 30 is permitted to return to normal position, the movement of selector arm 40 is in a counterclockwise direction and away from coupler 66 to unblock gear wheel 48 which is now free to be rotated through the bias of hammer 24 to where catch portion 38 and sear arm 36 become engaged to releasably hold the hammer in cock position, when the trigger reaches normal position. Thus, when bolt 14 is locked in battery position and automatic sear 102 consequently moved to unlock position, the firearm may be operated to fire another round when trigger 30 is re-actuated.

If the firearm is to be operated in automatically limited bursts, lever 96 is rotated in a clockwise direction to the next one of the indexing indentations 100. Whereupon, the camming engagement of secondary ramp portion 90 with angular surface 94 moves coupler 66 along shaft 64 until secondary step portion 92 is in engagement with foot portion 82, and arm portion 70 is engageably aligned with sprocket wheel 54. Thereby, when trigger 30 is actuated, the action of the firing mechanism will be similar to that described above except that firing will continue uninterruptedly through the cooperation of automatic sear 102 with hammer 24 until sprocket wheel 54 is rotated through the cooperation of the hammer and gear wheel 48 into engagement with coupler 66 held forwardly by trigger 30. Whereupon, firing will be automatically stopped but may be resumed for another burst after trigger 30 is returned to normal position, because through the return of the trigger to normal position with resulting movement of hammer 24 to cocked position, the previously engaged one of the teeth 52 is rotated past the position to be engaged by coupler 66, and the control of the hammer is transferred from Geneva device 44 to sear arm 36.

It is apparent that the number of rounds in the burst depends upon the number of firing cycles required to rotate sprocket wheel 54 in a complete revolution. In the present embodiment, Geneva device 44 is rotated 90° during each operating cycle, but it is apparent that this may be varied by changing the number of teeth provided on the gear wheel and making the necessary changes on the hammer so that the Geneva device will be rotated one tooth pitch during each operating cycle. It is also apparent that the firearm may be selectively adjusted to different combinations of bursts by adding to the Geneva device sprocket wheels having different amounts of sprockets, as shown by Fig. 7, and by having coupler 66 selectively cooperable therewith.

To fire the firearm continuously and with trigger control, lever 96 is indexed whereby selector 76 is free of engagement with foot portion 82 so that the coupler 66 is biased by spring 72 along shaft 64 to normal position and arm portion 70 is aligned with spacer 56. Thereby, when trigger 30 is actuated to fire the firearm, the firearm will continue to fire by means of automatic sear 102 until the trigger is released to releasably hold hammer 24 in cock position, as coupler 66 is free from blocking engagement with gear wheel 48 or sprocket wheel 54.

When the firearm is to be made inoperative, lever 96 is rotated in a counterclockwise direction to "Safe" position whereby selector 76 is rotated into position to block counterclockwise rotation of Geneva device 44 as is best shown in Fig. 1. If hammer 24 is in cock position when lever 96 is rotated to "Safe" position, the camming engagement of the perimeter of cam portion 80 with the adjacent one of the sides 50 rotates gear wheel 48 in a

clockwise direction. Consequently, as cog portion 62 is in engagement with one of the teeth 52, rotation of gear wheel 48 is transferred to hammer 24 which is retracted thereby from cock position. If hammer 24 is resting in firing position due to the complete expenditure of ammunition or other reasons when lever 96 is rotated to "Safe" position, such hammer is locked in "Safe" position after being actuated to retracted action when the firearm is charged.

From the foregoing it is clearly apparent that there is herein provided a novel firing mechanism whereby an automatic firearm with a hammer-actuated firing pin may be readily regulated for firing a single round, bursts of a predetermined number of rounds, and continuously with such firing mechanism being simple and rugged in construction and positive in operation.

Although a particular embodiment of the invention has been described in detail herein, it is evident that many variations may be devised within the spirit and scope thereof and the following claims are intended to include such variations.

I claim:

1. In an automatic firearm provided with a reciprocal bolt, a firing mechanism including a housing in which there are provided a hammer pivotal from a firing to a retracted position by the bolt during movement thereof from a battery to a recoil position, a trigger mounted rearward of said hammer by means of a transversely disposed pin for pivotal movement between a normal and a retracted position, a selector arm integral with said trigger and disposed to extend upwardly above said pin rearward of said hammer, a Geneva device rotatably disposed between said selector arm and said hammer, a plurality of teeth on said Geneva device disposed for successive engagement by said hammer to rotate said Geneva device a portion of one tooth pitch during movement of said hammer from the retracted to the firing position and the remainder of the tooth pitch during movement thereof from the firing to the retracted position, a coupler pivotally disposed between said selector arm and said Geneva device for actuation by said selector arm into position for engagement by one of said teeth to stop rotation of said Geneva device and prevent movement of said hammer to the firing position when said trigger is in the retracted position thereof and said hammer engages another one of said teeth.

2. The device as defined in claim 1 wherein said Geneva device includes a gear wheel having said plurality of teeth formed thereon and said hammer includes a cog disposed thereon to successively engage said teeth during movement of said hammer to the firing position for rotating said gear wheel a part of a tooth pitch, and a lug disposed on said hammer for successive camming engagement with said teeth during subsequent movement of said hammer from the firing position for rotating said gear wheel the remaining portion of the tooth pitch whereby said gear wheel is rotated one tooth pitch during each operating cycle of the firearm.

3. The device of claim 1 wherein said Geneva device includes a gear wheel provided with a plurality of teeth successively engageable by said hammer for rotating said Geneva device one tooth pitch during an operating cycle of the firearm, and a plurality of sprocket wheels coaxial with said gear wheel with each of said sprocket wheels being provided with sprockets the number of which on any one of said sprocket wheels being less than that of said teeth, and wherein said coupler is selectively alignable with said gear wheel and said sprocket wheels and pivotally actuatable by said trigger into position to engage the selected one of said gear and sprocket wheels for automatically stopping the operation of the firearm after a burst determined by the relationship between the number of said teeth on said gear wheel and the number of sprockets on the sprocket wheel engaged by said coupler.

4. The device of claim 3 including a selector provided

with a cam having steps engageable with said coupler for indexing said selector into selective alignment with said gear wheel and said sprocket wheels and an outside perimeter engageable with said gear wheel for blocking movement of said hammer to the firing position to safety the firearm during any position of said hammer.

5. In an automatic firearm provided with a reciprocal bolt, a firing mechanism for selectively regulating the firearm to fire a single round, bursts of a predetermined number of rounds and continuously comprising a hammer pivoted from a firing to a retracted position by the bolt during movement thereof from a battery to a recoil position, a trigger pivotal between a normal and a retracted position, a sear arm extending from said trigger for engagement with a catch portion in said hammer for releasably holding said hammer in a cock position between said retracted and firing positions, a Geneva device including a gear wheel, a sprocket wheel and a spacer in coaxial relationship, teeth on said gear wheel numerically related to a fewer number of sprockets on said sprocket wheel so that the ratio therebetween is equal to the predetermined number of rounds, a cog on said hammer successively engageable with said teeth during movement of said hammer to the firing position for rotating said gear wheel a part of one tooth pitch, a lug extending from said hammer for engagement with the one of said teeth previously

engaged by said cog to complete the rotation of said gear wheel one tooth pitch during subsequent movement of said hammer to the retracted position, a coupler slidably and pivotally mounted for selective alignment with said gear wheel, sprocket wheel and spacer and disposed for pivotal engagement therewith, a selector member cammingly engaged with said coupler for selectively aligning said coupler with said gear wheel, sprocket wheel and spacer and being selectively engageable with said gear wheel to block rotation thereof for safetying the firearm, and a selector arm on said trigger engageable with said coupler when said trigger is in the retracted position for pivoting said coupler to blockingly engage the selected sprocket wheel and gear wheel for blocking rotation of said Geneva device and movement of said hammer to the firing position.
